DEODORANT POWDER

Henry E. Melton, Detroit, Mich., assignor to C. E. Jamieson & Company, Detroit, Mich., a corporation of Michigan

No Drawing. Application December 2, 1935,
Serial No. 52,615

7 Claims. (Cl. 167—92)

The invention relates to deodorant compounds and has for its object the obtaining of a deodorant powder which may be applied by sprinkling, and which in addition to its deodorant characteristic has other valuable properties which adapt it for use on bandages, pads, etc. To this end, the invention consists in the compound as hereinafter set forth.

It is known that certain materials and particularly certain peroxides act as deodorants, due to the fact that its oxygen is liberated when such a substance comes in contact with body secretions and excretions. It is, however, necessary to control the action of such materials and in addition to destroying the odor to provide an absorptive medium which will prevent penetration through fabrics. Further, if the material is used as a sprinkling compound it must be of such character as to permit of sifting through small apertures. My improved material has these desirable characteristics and consists essentially in the combination with the deodorant material, of a material having the property of absorbing and holding moisture. Also, a material in the nature of an astringent or coagulant and a neutral body material through which the other materials are distributed and which prevents the caking of the same.

A specific example of my improved compound is composed as follows:

Kaolin—9 lbs. 7 ozs. (1.8%)
Zinc peroxide—90 lbs. 9 ozs. (17.3%)

Zinc oxide—50 lbs. (9.5%)

Talcum—200 lbs. (38.1%)

Precipitated chalk medium—175 lbs. (33.3%)

The specific proportions above given are not essential as the ingredients do not chemically combine with each other. The active deodorant is the zinc peroxide; the absorptive material is the kaoline; the zinc oxide functions as an astringent or coagulant; the talcum and precipitated chalk form a neutral body and also serve to prevent caking and facilitate free flow through a sprinkler. If the quantity of kaolin is in-

creased less zinc oxide would be required. Also, the zinc peroxide after liberating its oxygen becomes zinc oxide and performs the function of this material. The quantity of talcum and chalk may be varied through a relatively large range, but I have found that for practical purposes the specific proportions above given are very effective.

In use, the material may be applied to a bandage, pad or napkin by sprinkling the desired quantity thereon. It will then operate to not only deodorize, but also to absorb and prevent the flow and penetration of secretions and excretions through the fabric.

What I claim as my invention is:

1. A deodorant powder comprising zinc peroxide, a moisture absorptive material and a neutral body material, all of said materials being in powder form intimately commingled.

2. A deodorant powder comprising zinc peroxide, kaolin, zinc oxide and a neutral body material.

3. A deodorant powder comprising zinc peroxide, kaolin, zinc oxide, talcum and precipitated chalk.

4. A deodorant powder comprising zinc peroxide (15% to 20%), kaolin (1% to 5%), zinc oxide (5% to 15%), talcum (20% to 40%), and precipitated chalk (25% to 35%).

5. A deodorant powder comprising the following materials substantially in the proportions given and in commingled powder form:

	Per cent
Kaolin	1.8
Zinc peroxide	17.3
Zinc oxide	9.5
Talcum	38.1
Precipitated chalk	33.3

6. A deodorant powder comprising essentially zinc peroxide and kaolin.

7. A deodorant powder comprising zinc peroxide from 15 to 20%, kaolin from 1 to 5%, and the balance a neutral body.

HENRY E. MELTON. 45
